UNITED STATES PATENT OFFICE.

SOL FISHER, OF CLEVELAND, OHIO.

METHOD OF HAIR WAVING.

Application filed September 9, 1925. Serial No. 55,395.

The present invention, relating as indicated to a method of and apparatus for hair waving, is more particularly directed to an improved method of carrying out the operation commonly termed "permanently waving" hair, which consists, as ordinarily carried out, in coiling a lock of hair tightly around a pin or wire form, enclosing this coiled lock of hair within a sealed chamber containing heating elements, usually electrical, and then supplying sufficient heat to the chamber to vaporize a small amount of liquid, usually oil and water, in the chamber to give a set to the coiled lock of hair.

15 The present invention is directed particularly to an improvement on this method of hair waving which consists in simultaneously removing any escaping vapor or liquid from the lower end of the chamber during the 20 heating operation in order to effectively prevent any burning of the scalp, which is many times caused by either the hot vapor or the condensed liquid dropping upon or coming in contact with the scalp. To the accomplishment of the foregoing and related ends, 25 said invention, then, consists of the means hereinafter fully described and particularly pointed out in the claims.

The annexed drawing and the following 30 description set forth in detail certain means and one mode of carrying out the invention, such disclosed means and mode illustrating, however, but one of various ways in which the principle of the invention may be used.

35 In said annexed drawing:—

Fig. 1 is a side elevation showing one 40 form of my improved apparatus in use in connection with a hair-waving mechanism; and Fig. 2 is a view in perspective of the 45 discharge nozzle of my improved cooling apparatus.

Referring now to Fig. 1, there is shown, in 45 outline, a human head 1 with one of the locks of hair 2 properly coiled and disposed within a heating element or chamber 3, which is ordinarily suspended either from the ceiling or from a suitable standard. This element 50 3 is of standard construction and need not be described in detail, except to state that it is hollow, permitting the introduction of a lock of hair coiled about a suitable form, and contains means for holding a small amount of liquid which will be vaporized upon the application of heat to the chamber, 55 the heat usually being supplied by a resist-

ance through which current is passed from connections 4. In practice it has been found that, due usually to carelessness of the operators, there is a considerable risk of injury to the scalp during this operation because 60 of the difficulty of completely sealing the chamber 3, which permits either the heated vapor or the condensed liquid to leak down through the end of this chamber and fall upon the scalp, and in many cases very 65 severe burns have resulted from this cause.

My improved apparatus is a method and apparatus to prevent the above burns, the apparatus consisting of a frame or casing 5, in which are mounted a motor 6, here shown 70 as electrical, and a fluid pump 7, the pump being directly connected to the motor and driven thereby. A discharge conduit 8, leading from the pump, extends upwardly, being carried within a hollow standard or conduit 75 9 mounted on the top of the casing 5 and leading out therefrom through an opening 10, which is adjacent to a tray 11, upon which the extending portion 12 of the conduit 8 may be coiled when not in use. The 80 conduit 8, at least from its point of exit from the conduit 9, is flexible and terminates in a small flattened nozzle 13 which is adapted to discharge air at high speed and to spread the same in a fan-shaped area when discharged. A supply line for the electric motor, consisting of wires 14, extends through an opening 15 in the side of the frame 5, while a switch 16 is disposed at the top of the standard 9 and is connected by a 85 suitable line 17 to the motor.

The operation of the apparatus just described consists in spreading a considerable volume of air transversely of the locks of hair 2 during the waving operation, or, in other words, passing a considerable current of air over the various parts of the scalp during the heating or waving operation in order to remove from the vicinity of the scalp any vapor or condensed liquid which 95 may leak from the lower ends of the heating chambers 3.

The present method of hair waving is not only very much more comfortable for the customer because of the very much lower 100 temperature at which the head is maintained during the heating operation, but is also very much safer and slightly more rapid because of the less care which is now required in sealing up the ends of the heating chambers, 110

since the leakage of vapor or liquid is in the present method removed, and the risk of burning is eliminated.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In a method of waving hair, the steps which consist in heating a coiled lock of hair

while spraying a considerable volume of cool air between the scalp and the adjacent portion of such coiled lock.

2. In a method of waving hair, the steps which consist in heating a coiled lock of hair within a closed chamber in the presence of a vapor while simultaneously removing any vapor escaping toward the scalp by a blast of cool air directed across the scalp.

Signed by me, this 5th day of September, 1925.

SOL FISHER.
